UNITED STATES PATENT OFFICE.

JAMES J. JENNINGS, OF OAK PARK, ILLINOIS, ASSIGNOR TO ARTHUR H. BOETTCHER,
TRUSTEE, OF CHICAGO, ILLINOIS.

FILE-CARD HOLDER.

Application filed November 17, 1920. Serial No. 424,620.

To all whom it may concern:

Be it known that I, JAMES J. JENNINGS, a citizen of the United States, residing at Oak Park, in the county of Cook and State of Illinois, have invented a certain new and useful Improvement in File-Card Holders, of which the following is a full, clear, concise, and exact description, reference being had to the accompanying drawings, forming a part of this specification.

My invention relates to file card holders.

The fundamental object of the invention is to provide a holding device designed to hold in predetermined position any of the file cards of such filing systems as employ a plurality of file cards arranged in overlapping relation on a file card frame. This class of filing systems has illustration in rotary card files wherein a series of these file card frames are hinged as leaves in a rotatable support, and in other forms of filing apparatus wherein these file card frames are hinged in straight line series on a suitable supporting frame, or otherwise arranged for ready accessibility. In these various filing devices, in order to expose the data contained on these file cards it is necessary to raise or swing back all of the file cards above the desired card to be examined and to hold these cards in raised position while the data is being noted or transcribed. This makes the use of the cards inconvenient, particularly when it is necessary to examine or copy down considerable data from the file card, inasmuch as it necessitates the use of one hand to hold the superposed card in raised position. This is also bothersome inasmuch as it prevents one from using the other hand in holding the pad, book, or other writing surface upon which the transcription is being made, and prohibits one from leaving the file momentarily without losing the particular card selected. The present form of file card holder is intended to obviate these difficulties by providing card-holding members which are disposed on each side of the card file frame and which are adjustable along the length of the frame for engaging and holding in raised position any file card on either side of the frame. These card-holding members are so arranged that the operation of shifting them to any desired point along the card frame and of moving them into and out of engaging relation with the desired card can be performed with the

greatest ease and facility. The present file card holder may be embodied as a unitary part of the file card frame, or may be constructed as an appliance or attachment adapted to be fitted upon the frame.

Owing to the comparatively low cost of these file card frames, it is desirable that a file card holder be of inexpensive manufacture, and hence it is the further object of my invention to provide a simplified construction of file card holder consisting of a minimum number of parts, preferably sheet metal stampings, and capable of manufacture at a minimum cost.

The embodiment illustrated in the accompanying drawing represents a preferred form of my invention; it being understood that additions and modifications may be made thereto within the scope of my invention.

In the drawing:

Figure 1 is a fragmentary view of a rotary card file illustrating in elevation one of the file card frames with my improved card holder applied thereto;

Figure 2 is an enlarged horizontal sectional view through the vertically adjustable runner;

Figure 3 is a transverse sectional view taken on the plane 3-3 of Figure 2;

Figure 4 is a fragmentary sectional view taken on the plane of the line 4-4 of Figure 1, illustrating the cooperation of the card holder with the hinged file cards; and

Fig. 5 is a fragmentary detail view illustrating the rotatable supporting standard, carrying the vertical card frames.

The file card frame 5 is constructed of outer and inner channel members 6 which are connected at top and bottom by horizontal bars 8 and 9, these four frame members defining a narrow vertical frame for receiving the cards 11. The inwardly extending ends of the horizontal frame members 8 and 9 have pivotal mounting in a central rotatable supporting standard 4, whereby any desired file card frame may be revolved into convenient position and each frame may be swung to expose either side. The file cards 11 have a hinge mounting on the frame 5 so that they may be readily turned back to expose either side of any particular card, the several cards being superposed in overlapping relation, one above the other with each succeeding lower card projecting to expose

a name 12 or other indicia indicating its contents. The cards on the reverse side of the frame are arranged in identical relation. The preceding description will suffice to illustrate a conventional form of card file or index, the application of my invention to this form of card file being illustrative of the application and utility of the card holder with other forms of card files not of the rotary type.

In the present embodiment the card-holding device is illustrated in the form of an appliance or attachment, and in this form comprises a vertical guide rail 14 having its ends bent horizontally as indicated at 15 and 16 to engage with the horizontal frame members 8 and 9. The guide rail 14 is of channel-shaped section, as illustrated in Figure 2, and the channel-shaped ends 15 and 16 are thus made to embrace the edges and sides of the horizontal frame members 8 and 9, the device being applied by sliding these end portions 15 and 16 lengthwise over the frame members. The side flanges of the horizontal extensions 15 and 16 are provided with inwardly punched depressions 17-17 which are adapted to engage the outer frame member 6 and limit the inward motion of the horizontal extensions 15 and 16 along the frame members 8 and 9. This is for the purpose of avoiding interference between the card-holding device and the index tab 18 which is generally provided at the outer edge of each file card frame for indicating the alphabetical order of the card frames.

Adapted for motion along this guide rail 14 is a runner 20 which carries the two card-holding arms 21 and 21' at opposite ends thereof. Like the guide rail 14, this runner 20 is preferably constructed of sheet metal stampings, and comprises a box-like stamping 22 defining the inner and top and bottom walls of the runner 20. The end walls 23 of the housing member 22 are formed by bending up extensions from the bottom wall 24, these extending portions of metal terminating flush with the upper surface of the top wall 25. The outer open face of the housing member 22 is closed off by a plate 26 which is formed with a marginal flange 27 extending around all sides of the plate 26 and engaging over the top, bottom and end walls of the housing member 22. The guide rail 14 extends through slotted openings 28 in the top and bottom walls 25 and 24, these slotted openings 28 extending forwardly to the front edges of the top and bottom walls 25 and 24 so that the housing member may be conveniently assembled over the guide rail 14 after the horizontal ends 15 and 16 have been bent therein. The front plate 26 is secured to the housing member by two pins 29-29, each of which is passed downwardly through the flanges 27-27 and the top and bottom walls 25-24 at a point

intermediate the guide rail 14 and the end wall 23. A leaf spring 31 consisting of a single strip of flat spring metal is extended through the length of the housing member 22 and is bowed between the inner faces of the pins 29 and the outer flat face of the guide rail 14. The extremities of the spring 31 extend into engaging relation with the ends of the card-holding arms 21 and 21' and function as detents or biasing means for holding the arms in their two positions. Each of the arms 21-21' is pivoted upon the inside of its respective end wall 23 upon a pivot pin 32. At each end, the top wall 25 is provided with a slotted recess 33 which is made continuous with a similar vertical recess 34 in the inner wall 35 of the housing member. Each of the arms 21-21' plays between the limits of these adjoining slotted openings. The lower edge of each arm 21-21' is beveled as indicated at 36 to present a flat surface to the leaf spring 31 when the arm is in its inclined card-engaging position so that the spring can function to retain the arm in this position. When the arm is in its normal, upright position (indicated in dotted lines in Figure 1) the end of the leaf spring 31 bears against the vertical flat edge of the arm and thus retains it in this position, and, similarly, when the arm is in its card-engaging position (indicated in full lines in Figure 1) the engagement of the leaf spring 31 with the beveled lower edge 36 will retain the arm in this position. The tensional engagement of the spring 31 with the front of the channel rail 14 also retains the runner in any set position along the rail 14, and thus the spring 31 functions as a resilient detent for the runner 20 as well as for the arms 21-21'.

In the use of the card holder, after the proper card has been raised, together with the superposed cards above the same, the runner 20 is slid lengthwise along the guide rail 14 to a point adjacent the lowermost raised card and the arm 21 or 21' is then swung diagonally into position to engage the said card and hold the same in raised position for exposing the record data on the rear face of this card or on the front face of the next lower card. The action of the leaf spring 31 engaging the front of the guide rail 14 imposes just sufficient tension upon the runner 20 to retain it in any set position, but without materially retarding the adjusting motion of the runner along the guide rail. This spring, moreover, retains the inner ends of the two slotted openings 28 in tensional engagement with the edges of the guide rail 14 and thus prevents any tendency of the runner 20 to wobble laterally on the guide rail.

The same general form and construction may be followed when the card holding device is embodied as a unitary part of the

file card frame 5. For example, in such embodiment, the end portions 15 and 16 might also constitute the top and bottom members for the card frame 5. As an alternative construction, independent guide rails 14 may be provided for each side of each file card frame, these two guide rails carrying independent runners 20 having separate card holding arms 21 for engaging the cards on their respective sides of the file card frame.

I do not intend to be limited to the details herein shown and described, except as they are set forth in the appended claims.

I claim:

1. In combination, a card frame adapted to carry a plurality of cards having pivotal movement, means carrying the weight of said cards and slideable along one dimension of said frame for holding said cards in a desired position, and means for locking said first means in holding position.

2. In combination, an open frame having substantially opposed parallel members, a plurality of file cards pivotally carried on said open frame, a standard having its ends attached to said opposed parallel members, and means adjustable along said standard for projection into the path of said cards.

3. A file card holder adapted for cooperation with the cards of a file card frame, comprising a vertical guide member extending parallel to the vertical edge of the file card frame, a runner movable longitudinally along said guide member, and an arm carried by said runner and adapted to be moved into and out of engaging relation with the cards on said frame, and means for holding said arms in engaging relation against the weight of the cards.

4. In combination, a vertical file card frame having file cards on opposite sides thereof, a guide member extending parallel with the vertical edge of said frame, a runner movable longitudinally along said guide bar, means for retaining said runner at any set position along said guide rail, a pair of card-holding arms carried by said runner and adapted for engagement with the cards on opposite sides of said file card frame, each of said arms being pivoted to said runner and being adapted for swinging motion into and out of engagement with the file cards.

5. In combination, a plurality of vertical file card frames having hinged motion on a common standard, a vertical guide rail extending along the outer edge of one of said frames, a runner movable along said guide rail, card-holding arms carried by said runner and adapted to hold the cards on

opposite sides of said frame, each of said arms having a pivotal swinging motion into and out of engagement with said cards, and resilient detent mechanism for retaining said runner in set position on said guide bar and for retaining said arms in their operative and inoperative positions.

6. In combination, a file card frame having file cards on opposite sides thereof, a guide rail extending parallel to the vertical edge thereof, a runner shiftable along said guide rail, said runner comprising a housing member slotted to engage over said guide rail, a cover member closing off said housing member, card-holding arms extending into said housing member through slots in the ends thereof, said arms being pivoted to the end walls of said housing member, said arms being movable into and out of card-holding position with the cards on their respective sides of said frame, and a spring member in said runner bearing against said guide bar for retaining said runner in any set position along said guide bar, the ends of said spring member engaging with the ends of said card-holding arms for retaining said arms in their different positions.

7. In combination, an open frame for carrying a plurality of pivotally mounted file cards, a standard running substantially perpendicular to the axes of said cards, and means adjustable along said standard for projection into the path of said cards.

8. In combination, a substantially rectangular open frame, a plurality of file cards pivotally carried within said open frame, a U-shaped standard having its parallel legs embracing certain sides of said frame, and means adjustable along said standard for projection into the path of said cards.

9. In combination, a card file frame for carrying a plurality of pivotally mounted cards, a guide member on said frame, a runner on said guide member, means on said runner and swinging in the path of said cards, and means carried by said runner for holding said first means in or out of the path of the cards.

10. In combination, a file card frame for carrying a plurality of pivotally mounted cards, a guide member on said frame, a runner on said guide member, arms on said runner for swinging into engagement with said cards, and means for holding said runner and said arms in set position.

In witness whereof I hereunto subscribe my name this 5th day of November, 1920.

JAMES J. JENNINGS.
